UNITED STATES PATENT OFFICE.

GEORGE P. ABORN, OF BROOKLINE, MASSACHUSETTS, ASSIGNOR TO WORCESTER PUMP AND MACHINERY CORPORATION, A CORPORATION OF VIRGINIA.

ENGINE VALVE.

Application filed July 30, 1918. Serial No. 247,364.

To all whom it may concern:

Be it known that I, GEORGE P. ABORN, a citizen of the United States, residing at Brookline, county of Norfolk, and State of Massachusetts, have invented certain new and useful Improvements in Engine Valves, fully described and represented in the following specification and the accompanying drawings, forming a part of the same.

10 This invention relates to steam engines equipped with fluid actuated valves and especially to such valve mechanism for engines used in direct acting pumps.

15 The object of the invention is to provide a simple and improved valve mechanism for working the steam expansively and acting to slow down the piston near the end of its stroke in order to allow the valves in the pump to seat quietly and with little shock 20 and to secure an easy reversal of the piston stroke. This result is secured by an auxiliary valve acting to cut off the steam from the main valve for using the steam expansively and then controlling the reversal 25 of the main valve, the action being similar to that of my prior Patent No. 1,055,996, dated March 18, 1913, but the present invention including improved means for securing this result.

30 In the drawings—

Figure 1 is a section longitudinally of the steam cylinder on the lines 1—1 of Figs. 2 and 4.

35 Figure 2 is a section longitudinally of the auxiliary cylinder on the lines 2—2 of Figs. 1 and 3.

Figure 3 is a section on the line 3—3 of Fig. 2.

40 Figure 4 is a sectional plan view of the auxiliary cylinder ports and passages.

Figure 5 is a plan view of the steam cylinder showing its ports and passages; and

45 Figure 6 is a side elevation of the engine showing suitable tappet gear for operating the auxiliary valve rod.

The main engine cylinder 5, within which operates the piston 25 secured to piston rod 26, is provided with a seat for the auxiliary cylinder 4 which preferably is secured 50 thereto at right angles to the axial line of the main cylinder. This auxiliary cylinder seat is provided with the usual ports and passages 8, 10 connecting with the opposite ends of the cylinder 5. This seat is also 55 provided with suitable inlet and exhaust

ports 27, 28 for the auxiliary cylinder connected by passages to the steam inlet port 29 and exhaust port 30.

The auxiliary cylinder 4 is provided at its ends with annular ports 11, 12, connected by 60 a suitable passage 28' to the exhaust port 28, and annular ports 7, 9 connected by passages 8', 10' respectively to the ports 8, 10 leading to the steam cylinder ends. That portion of each end of the auxiliary cylinder 65 within which the piston portions of the main slide valve 1 operate is provided with the usual liner 3 having rings of ports registering with the annular ports in the auxiliary cylinder walls.

70 Referring now particularly to Figures 2 and 3, each piston portion of the main slide valve 1 is formed to provide a comparatively wide annular exhaust port 32 and a narrow annular inlet port 33 which are connected 75 respectively to the exhaust passages 31 and to inlet passages 17, 16 at opposite ends of the valve, these exhaust and inlet passages extending longitudinally through the piston portions of the main valve and connecting 80 to ports controlled by the auxiliary valve.

75 The auxiliary valve seat 34 is equipped with the steam inlet ports 21 and 20 connecting respectively with passages 17 and 16, for delivery of steam to the ports 9 and 7, 85 ports 15 and 13 communicating respectively by passages 19 and 18 with the auxiliary cylinder ends, and an exhaust port 14 connecting exhaust passages 31 for exhaust of steam used for shifting the main slide valve 1.

90 Mounted upon this valve seat is the auxiliary valve 2 provided with combined inlet and cut off ports 22, 23 and an exhaust cavity 24 for connecting the ports 15, 13 with the exhaust port 14. The auxiliary valve 2 95 is moved by valve rod 6 which is operated by the main piston rod 26 through actuating arm (a) carrying tappet (b) which engages one or the other of the adjustable collars (c), or through other suitable means.

100 The operation of the mechanism is as follows:

Assuming the main valve to be at the right, as shown in Figure 2, being held in this position by steam admitted to its left 105 by port 15 and passage 19, steam will pass through port 23 in the auxiliary valve, port 20 and passage 16 in the main slide valve, to annular port 33. As shown in Figures 2 and 3 annular port 33 is in communication 110

with port 7 in the auxiliary cylinder so that steam passes through port 8 in the main cylinder to the left of the main piston 25, causing it to move to the right. At the same time steam will exhaust from the opposite side of the main piston through passage and port 10, port 9 in the auxiliary cylinder and port 32 in the main slide valve to port 12, and thus to exhaust port 28 and 10 exhaust 30. As the main piston 25 reaches a predetermined point in its stroke, depending upon the point of cut off desired, the tappet (b) engages with a collar (c) on valve rod 6, moving the auxiliary valve 2 15 to the left in Figure 1 until the steam port 20 in the main valve is closed by the edge of port 23 in the auxiliary valve, thus cutting off the steam supply to the main cylinder which from this point to release works 20 expansively, and simultaneously opening the auxiliary port 13 in the main valve and admitting steam to the right of the main valve through passage 18. Further movement of the auxiliary valve connects 25 auxiliary port 15 in the main valve with cavity 24 permitting the exhaust of steam from the left of the main valve through passage 19, and ports 15 and 14 to one of the exhaust passages 31 in the main valve 30 which passages are always in communication with the exhaust port 28 through one or the other annular port 32 and either port 11 or 12. The main valve will now move to the left and will continue its travel until 35 the auxiliary port 15 is closed by the edge of the cavity 24 when the main valve will come to rest in its left-hand position registering the proper ports for the return stroke of the main piston.

40 The construction as thus shown and described is the preferred embodiment of the invention; but it will be understood that the invention is not limited to the specific arrangement of parts illustrated, but that 45 the broad features of the invention, as defined by the claims, may be embodied in other constructions.

What is claimed is:—

1. The combination with a main cylinder, 50 of an auxiliary cylinder, a fluid actuated main valve having passages running lengthwise therethrough for delivery of steam to the main cylinder and to the auxiliary cylinder ends, a valve face on the main valve, 55 an auxiliary valve cooperating with said valve face, and ports by which the auxiliary valve controls the delivery of steam to said passages.

2. The combination with a main cylinder, 60 of an auxiliary cylinder thereon provided with ports for the delivery of steam to and from the cylinder ends, a fluid actuated main piston valve operating within the

auxiliary cylinder and controlling its ports, a valve face on the main valve, passages running lengthwise through said main valve and connecting the ports of said main valve with said valve face, and an auxiliary valve 65 cooperating with said valve face to control through said ports the movement of the main valve.

3. The combination with a cylinder, of an auxiliary cylinder thereon provided with 70 ports for the delivery of steam to and from the cylinder ends, a fluid actuated main piston valve located within the auxiliary cylinder and controlling its ports, a valve face on the main piston valve, passages running lengthwise through said main piston valve and connecting the ports of said main valve with said valve face, an auxiliary valve cooperating with said valve face to control through said ports the movement of 75 the main valve and acting to cut off the supply of fluid to the main valve for use of the steam expansively in the main cylinder.

4. In combination, a main valve having its end portions forming piston valves with 80 annular inlet and exhaust ports, and its central portion forming a valve face, an auxiliary cylinder in which the main valve moves having annular steam ports controlled by said main valve, an auxiliary 85 valve on said central valve face, ports controlled by said auxiliary valve for controlling the supply of steam to the annular ports of the main valve, and to the ends of the auxiliary cylinder for moving the 90 main valve, and passages extending longitudinally through the main valve and connecting with said ports.

5. The combination with a main cylinder and its steam ports, of an auxiliary cylinder thereon having annular ports for steam supply and exhaust, a main valve in said auxiliary cylinder with its opposite ends forming piston valves controlling said annular ports and a valve face between said 100 piston portions, ports in said valve face, and passages 16, 17 extending longitudinally through the main valve for the supply of steam to the main cylinder, and passages 110 18, 19, and 31 extending longitudinally through the main valve for the supply and exhaust of steam to and from the ends of the auxiliary cylinder for moving the main valve, and for delivery of such exhausted steam to the auxiliary cylinder exhaust 115 ports and an auxiliary valve controlling said valve face ports and acting to cut off the steam supply to the main valve for using the steam expansively in the main cylinder.

In testimony whereof, I have hereunto set my hand.

GEORGE P. ABORN.
